INVENTOR
GEORGE SACHNOFF

BY
John C. Gill ATTORNEY

UNITED STATES PATENT OFFICE.

GEORGE SACHNOFF, OF BROOKLYN, NEW YORK.

FASTENER FOR FUR GARMENTS.

Application filed September 30, 1921. Serial No. 504,501.

To all whom it may concern:

Be it known that I, GEORGE SACHNOFF, a citizen of Russia, and a resident of Brooklyn, in the county of Kings and State of New York, have invented certain new and useful Improvements in Fasteners for Fur Garments, of which the following is a specification.

The invention relates to clamp fasteners of the character employed for securing together the end portions of a fur scarf or other garment, it being customary to fashion one end of the scarf to approximately represent the head of an animal and to so embody the clamping features therein that they imitate the jaws of said head. Broadly speaking, animal heads or heads for fur scarfs of the character indicated are very old and have long been used. It has always been a source of considerable expense and vexation to manufacturers to build up in an effectual and secure manner the animal head for the scarf and secure the clamping members therein, and the purpose of my invention is to furnish means which greatly simplify and lessen the expense and materially expedite the building up of the animal head and the securing of the main body clamp therein. In the use of my invention the element of sewing is greatly reduced and the customary use of paste and glue in applying and shaping the head is entirely eliminated.

My invention resides in the novel features and combinations of parts hereinafter described, and particularly pointed out in the claims, and said invention will be fully understood from the following specification considered with reference to the accompanying drawings, in which:

Fig. 1 is a central vertical longitudinal section through the head end portion of a fur scarf equipped with a fastening device of clamp order constructed in accordance with and embodying my invention;

Fig. 2 is a like view of the same but illustrating a modification thereof consisting in the omission of certain features shown in Fig. 1, with respect to the lower jaw of the fastener or clamp;

Fig. 3 is a like view of a further modified embodiment of my invention;

Fig. 4 is a vertical transverse section taken on the dotted line 4—4 of Fig. 1;

Fig. 5 is a detached perspective view of one member of the upper clamping jaw of the device shown in Fig. 3;

Fig. 6 is a detached perspective view of a head piece I apply within the end of the fur garment and over the upper clamping jaw in the formation of an imitation of a head of an animal;

Fig. 7 is a perspective view taken from the bottom of the same;

Fig. 8 is a detached perspective view of a spring clamping finger which I apply upon the top of the upper jaw member to receive and secure the head piece shown in Figs. 6 and 7;

Fig. 9 is a detached perspective view of a cap or covering piece, preferably of celluloid, which I apply upon the top of the upper steel member and upon the bottom of the lower steel member of the main clamp to enclose and conceal the same;

Fig. 10 is a perspective view of the main steel clamp detached from the other features making up the finished fastener;

Fig. 11 is a detached perspective view of the lining for the mouth formed between the main jaw members of the clamp, the same being preferably of celluloid;

Fig. 12 is a detached perspective view of the covering member which I apply to the steel jaws of the clamp, the same showing the reverse side of the piece shown in Fig. 9 and also illustrating the covering member which I apply to the lower jaw of the clamp shown in Fig. 10;

Fig. 13 is a perspective view of a clamping spring which, when desired, I apply to the lower jaw of the clamp, Fig. 13 corresponding with Fig. 8 which illustrates the clamping spring which I apply to the upper jaw of the clamp;

Fig. 14 is a perspective view, taken from the top, of a lower jaw filler member I utilize in the construction shown in Fig. 1;

Fig. 15 is a perspective view of the same taken from the lower side thereof, and

Fig. 16 is a perspective view of a portion of the head end of a scarf employing the fastening features of my invention.

I will first describe the construction shown

2
in Fig. 1, which presents the more complete embodiment of my invention, and therein 20 designates one end portion of the usual scarf and 21 the head formed thereon supplemented by a snout 22 which will usually be of leather and sewed in position.

The fur portion of the head 21 is divided to provide for an upper jaw and a lower jaw, an elongated pocket 23 being formed 10 in the upper division of the head and an elongated and more shallow pocket 24 being formed in the lower division of the head. The pocket 23 is formed of the upper fur skin 25 and an inner piece of skin 26 from 15 which the fur has been substantially removed, the two pieces being sewed together at their meeting edges at the sides of the upper division of the head and receiving the snout 22. The lower pocket 24 is formed 20 between the bottom fur skin 27 and an upper inner piece of skin 28 from which the fur has been substantially removed, the two pieces 27, 28 being sewed together at the sides of the lower jaw.

25 Within the pocket 23 I insert a reasonably close-fitting head-piece 29, shown in detail in Figs. 6 and 7 and consisting of a forwardly tapered flat base 30, a forehead cross-piece or bar of cork or the like 31 thereon, a 30 forwardly extending bar or nose bridge-piece 32 secured centrally on the upper side of said base 30 and a longitudinal centrally disposed pocket 33 of metal secured to the lower side of said base.

35 The eyes 34 are of usual type and their tack portions 35 are forced through the top skin 25 at opposite sides of the nose-bridge 32 and into the cross-bar 31, in the manner I seek to indicate in Fig. 6.

40 I secure the head-piece 29 within the pocket 23 without the use of glue or sewing but with the employment of a spring tongue 36 (Figs. 1 and 8), which I rivet, at its rear end, to the handle 37 of the upper jaw member 38 of the main clamp 39 shown separately in Fig. 10. When the clamp 39 is finally applied to position through an opening left in the fur at 40 for that purpose, the spring tongue 36 is passed forwardly into the 45 pocket 33, which it snugly fits, and acts to firmly position the head-piece 29 and prevent lateral play thereof and also as an auxiliary clamp to bind said head-piece firmly down against the lower skin piece 26 and the upper jaw of the clamp 39. In a 50 less expensive construction than I show in Fig. 1 I will permit the piece of skin or fabric 26 to lie directly upon the upper jaw member 38 of the clamp 39 where it will be securely held by the clamping action against the same of the head-piece 29 and spring tongue 36, but by preference I apply upon said jaw member 38 a cap or covering piece 41, of celluloid or other suitable material, 55 of the form shown in Figs. 9 and 12, said

cap or covering piece conforming to the general outline of and receiving said jaw member 38 and having a depending edge flange 42 which conceals the edges of the jaw member 38. The cap 41 has a rear 70 tongue 43 which lies below the rear end of the spring tongue 36 and upon the clamp handle 37, and said cap is secured in position by one of the rivets 44 utilized in securing said spring tongue upon said handle, 75 as shown in Fig. 1.

The clamp 39 comprises the upper jaw member 38 having a handle 37 and a corresponding lower jaw member 45 having a handle 46, and said members are pivoted 80 together, at 47, in a usual way and equipped with a customary spring 48 acting to close the jaw members and parts connected therewith.

The lower jaw member of the clamp 39, 85 in the construction shown in Fig. 1, has a spring tongue 49 secured to it, said tongue being separately shown in Fig. 13 and corresponding in every respect with the spring tongue 36 secured upon the upper jaw member of the clamp. The lower jaw member of the clamp 39 has an inverted cap or covering piece 50 (Fig. 12) of celluloid or other suitable material applied to its lower side, said cap or covering piece 50 being of 90 the same form and construction, except for being inverted, as the cap or covering piece 41 applied upon the upper jaw member. The cap 50 conforms to the outline of and snugly receives the lower jaw 45 and has an 95 upwardly extending edge flange 51 and a rearwardly extending tongue 52 which is secured to the clamp-handle 46 and between said handle and the rear end of the spring tongue 49 by one of the rivets 53 by which 100 the tongue 49 is secured to the lower member of the clamp 39.

Within the lower jaw of the head 21 and located in the pocket 24 and between the lower fur skin 27 and upper inner piece of 110 skin 28, is a filler-piece 54, shown in details in Figs. 14 and 15, which is flat and tapers forwardly and helps to form and shape said lower jaw. The filler piece 54 has on its lower side and extending centrally thereof 115 a longitudinal pocket 55 into which, in the assembling of the parts of the head, the spring 49 is thrust for securely holding the filler-piece 54 in position and against the upper wall 28 of the pocket 24.

The upper cap member 41 has its edge flange 42 extended downwardly and the lower cap member 50 has its corresponding flange 51 extended upwardly, and to said flanges I secure by cement or other means the upper and lower oppositely projected flanges 56, 57 respectively formed on the lining 58 (Fig. 11) for the mouth of the head 21 and whereby said lining becomes secured in place. The lining 130

58 is preferably in one continuous strip of celluloid or other suitable material folded over at its middle portion along the hinge-line 59 so as to line the roof and bottom of 5 the mouth, and said lining is preferably formed with teeth 60 which stand inwardly from the flanges 56, 57.

The skin portions 27, 28 forming the pocket 24 for the lower jaw may in the assembly of the parts first have the filler piece 54 inserted therein and be then applied to the clamp by slipping the pocket 55 inwardly on the spring tongue 49, after which the inner end of the skin 27 will be fastened 15 to the body of the scarf at the point 40.

The head 21 constructed as shown in Fig. 1 and as hereinbefore described may be quickly formed from parts ready to be assembled and without the expense and 20 excessive skill and labor at present required in the formation of animal heads on scarfs.

The more complete embodiment of my invention is that shown in Fig. 1, but many of the advantages of my invention may be 25 realized without using all of the features represented in Fig. 1, as for illustration, as I show in Fig. 2, I may omit the bottom pocket 24, the skin portions 27, 28 forming that pocket, the lower jaw filler piece 54 and the spring tongue 49, and these lower 30 jaw parts being omitted, I have the animal head shown in Fig. 2 which possesses all the other parts of Fig. 1 and is complete, efficient and attractive. I therefore number 35 Fig. 2 correspondingly with Fig. 1 since the description of Fig. 2 would be identical with that of Fig. 1 as to all the parts shown in Fig. 2. For light scarfs and small heads the construction shown in Fig. 2 is entirely sufficient, the lower cap member 50 then forming 40 the bottom of the lower jaw. For larger heads requiring for appearance, a fur covered lower jaw, I recommend the entire construction shown in Fig. 1, which differs from Fig. 2 only in the omission from Fig. 2 of the fur covered lower jaw.

In the modified construction shown in Fig. 3, I insert in the pocket 23 formed between the outer fur skin 25 and inner skin 26, a head-piece 61 having a base 62, cross-bar 63 and longitudinal bridge 64 corresponding with the parts of the head-piece 29 shown in Figs. 6 and 7. The head-piece 61 is the same as the head-piece 29, except that I omit 55 from the head-piece 61 the pocket 33 present on the head-piece 29; and in said modified construction the spring 65, which is a substitute for the spring 36, carries at its forward end a forwardly tapered plate 66 which clamps the skin portion 26 against the cap 41 for the upper clamp-jaw 38. In all other respects the construction shown in Fig. 3 is the same as that shown in Fig. 2. Fig. 5 shows the spring 65 and its plate 66, 60 which directly clamps the skin 26 against

the cap 41 instead of doing so, as in Figs. 1 and 2, indirectly through the pocket 33 forming a part of the head-piece 29. The clamping spring 65 is riveted to the handle 37 of the clamp 39, the same as is the spring 70 36. I present Figs. 3 and 5 as indicating that my invention may not be evaded by the omission of the pocket 33 from the inserted head-piece and the clamping of the skin 26 down by the direct action of the clamping 75 spring secured to the main clamp 39.

I am aware also of other modifications of my invention involving changes in the form and rearrangements of the clamping parts and therefore I do not wish to be limited 80 to the specific embodiments of the invention shown nor otherwise than the appended claims and the prior art may require.

What I claim as my invention and desire to secure by Letters Patent, is:

1. A clamp fastener of animal-head type for fur garments comprising a main body spring clamp having opposite pivoted together members affording clamping jaws and handles thereon, a preparatory pocket 90 formed in the skin above the upper clamping jaw, said pocket comprising the outer fur part and a lower ply secured along its edges thereto, a shaping head-piece insertible endwise into said pocket and an auxiliary spring clamp secured to said body clamp and entering said pocket and acting to bind downwardly against the lower ply thereof, the main upper clamping jaw being below said lower ply.

2. A clamp fastener of animal-head type for fur garments comprising a main body spring clamp having opposite pivoted together members affording clamping jaws and handles thereon, a preparatory pocket 95 formed in the skin above the upper clamping jaw, said pocket comprising the outer fur part and a lower ply secured along its edges thereto, a shaping head-piece insertible endwise into said pocket having a longitudinally extending pocket and an auxiliary securing spring clamp secured to said body clamp and entered within the pocket of and positioning said head-piece and also binding the same downwardly against said 100 lower ply, the main upper clamping jaw being below said lower ply.

3. A clamp fastener of animal-head type for fur garments comprising a main body spring clamp having opposite pivoted together members affording clamping jaws and handles thereon, a preparatory pocket 105 formed in the skin above the upper clamping jaw, said pocket comprising the outer fur part and a lower ply secured along its edges thereto, a shaping head-piece in said pocket, a mouth-lining between said jaws, a cap over the upper jaw defining the edge outline of the animal head and being below 110 said lower ply, and an auxiliary spring 115 120 125 130

clamp secured to said body clamp and extending within said pocket and acting to bind the lower ply of said pocket against said cap, said upper jaw being below said lower ply and between said cap and said mouth lining.

4. A clamp fastener of animal-head type for fur garments comprising a main body spring clamp having opposite pivoted together members affording clamping jaws and handles thereon, a preparatory pocket formed in the skin above the upper clamping jaw, said pocket comprising the outer fur part and a lower ply secured along its edges thereto, a shaping head-piece insertible endwise into said pocket having a longitudinally extending pocket, a mouth-lining between said jaws, a cap over the upper jaw defining the edge outline of the animal-head and being below said lower ply, and an auxiliary spring clamp secured to said main clamp and entered within the pocket of said head-piece and acting to bind said head-piece and lower pocket ply below it against said cap and the upper jaw of the main clamp.

5. A clamp fastener of animal-head type for fur garments comprising a main body spring clamp having opposite pivoted together members affording clamping jaws and handles thereon, a preparatory pocket formed in the skin above the upper clamping jaw, said pocket comprising the outer fur part and a lower ply secured along its edges thereto, a shaping head-piece insertible endwise into said pocket, a mouth-lining between said jaws, a cap over the upper jaw defining the edge outline of the animal-head and being below said lower ply, and an auxiliary spring clamp secured to said body clamp and extending within said pocket and acting to bind the lower ply of said pocket against said cap, said lining having an upwardly extending edge flange around the top of the mouth and said cap a downwardly extending edge flange and said flanges being secured together, the upper jaw of the main clamp being between said cap and the top of said mouth-lining.

6. A clamp fastener of animal-head type for fur garments comprising a main body spring clamp having opposite pivoted together members affording clamping jaws and handles thereon, a head formation above and connected with the upper jaw, a lower head formation below the lower jaw consisting of a pocket initially open at its rear end and an auxiliary spring clamp secured to the lower jaw of the main clamp and entered within said pocket and acting to bind against the upper ply thereof, the lower main clamping jaw being above said upper jaw.

7. A clamp fastener of animal-head type for fur garments comprising a main body-

spring clamp having opposite pivoted together members affording clamping jaws and handles thereon, a head formation above and connected with the upper jaw, a lower head formation below the lower jaw consisting of a pocket initially open at its rear end, a filler inserted into said pocket defining the edge outline of the animal-head and having a longitudinal pocket and an auxiliary spring-clamp secured to said main clamp and entered within the pocket of said filler and binding the filler and the upper ply of the lower head formation against the lower surface of the lower main clamping jaw.

8. A clamp fastener of animal-head type for fur garments comprising a main body spring clamp having opposite pivoted together members affording clamping jaws and handles thereon, a head formation above and connected with the upper jaw, a lower head formation below the lower jaw consisting of a pocket initially open at its rear end, a mouth lining between said jaws, a cap over the lower side of the lower jaw defining the edge outline of the head and an auxiliary spring clamp secured to said main clamp and entered within said pocket and acting to bind the upper ply thereof against said cap.

9. A clamp fastener of animal-head type for fur garments comprising a main body spring clamp having opposite pivoted together members affording clamping jaws and handles thereon, a head formation above and connected with the upper jaw, a lower head formation below the lower jaw consisting of a pocket initially open at its rear end, a mouth-lining between said jaws, a cap over the lower side of the lower jaw defining the edge outline of the head, and an auxiliary spring clamp secured to said main clamp and entered within said pocket and acting to bind the upper ply thereof against said cap, said lining having a downwardly extending edge flange around the bottom of the mouth and said cap an upwardly extending corresponding edge flange and said flanges being secured together, and the main lower clamping jaw being between said cap and said lining and above said pocket.

10. A clamp fastener of animal-head type for fur garments comprising a main body spring clamp having opposite pivoted together members affording clamping jaws and handles thereon, a lining of mouth formation between said jaws, a cap over the upper jaw having a depending edge flange, a cap under and enclosing the lower jaw and having an upwardly extending edge flange, said lining having an upwardly extending edge flange secured to the flange of said upper cap and a downwardly extending edge flange secured to the flange of said lower

cap, and said caps being secured to said clamp members, and auxiliary springs secured to said main clamping jaws to enter the upper and lower head formations respectively and bind the same against said caps respectively, the upper main jaw being between its cap and the mouth lining and the

lower main jaw being between its cap and the mouth lining.

Signed at New York city, in the county ¹⁰ of New York and State of New York, this 28th day of September, A. D., 1921.

GEORGE SACHNOFF.
